WAVE-ACTUATED BOAT PUMP
Arnold Delaney, Government Road, Nord's Wharf,
New South Wales, Australia
Filed Apr. 13, 1962, Ser. No. 187,303
Claims priority, application Australia Apr. 17, 1961
6 Claims. (Cl. 114—183)

This invention has been devised to provide a boat pump adapted for attaching to a hull on the outside when a boat is moored. The pump incorporates a float arranged so that waves or movement of the boat will cause the float to actuate the pump. The pump is particularly devised to remove water from the bilge of unattended small craft.

This wave actuated pump comprises a plunger pump, means for removably attaching the pump to the outside of a boat hull, means connecting the plunger of the pump to a float in the water in such manner that the plunger is reciprocated by the float due to wave movement or boat movement, and a pump suction pipe is extended into the boat bilge. Preferably the pump barrel is open on the discharge side and is so located that it is automatically maintained primed.

One embodiment of the invention is described with reference to the annexed drawings wherein:

FIG. 1 is a perspective view of the invention attached to the outside of a boat hull.

FIG. 2 is an elevation of the invention with parts of the pump and the attaching means shown in section and with part of the attaching means broken away.

As illustrated, the pump consists of a pump barrel 1 having a sludge sump 2 at the bottom thereof, an inlet connection 3 above the sump 2, and an outlet 4 at the top. A valve seat 5 is fixed in the pump barrel 1 above the inlet 3 and has a foot valve 6 to register therewith. A plunger 7 in the pump barrel 1 has a valve seat 8 formed therein and a head valve 9 seats thereon.

The plunger rod 10 is connected at one end to the plunger 7 and at its other end it is connected to a lever 11. The lever 11 is connected at one end to a float 12 and its other end it is fulcrumed as at 13 to a bracket 14 fixed on and projecting from an offset limb 15 of base member 16. The bracket 14 has a screwed opening 17 in the bottom thereof and the pump barrel 1 is mounted in the opening 17, which is also in communication with outlet 4. The bracket 14 also has spaced limbs 18 thereon which, with the body of the bracket 14, provide side guides and upper and lower stops for the lever 11. The base member 16 as illustrated, is re-

2

movably mounted on a mounting plate 19 which is fixed to the outside of the boat hull 20.

The float 12 is saucer shaped and has a fine edge 21. The float 12 is so constructed that it is normally submerged to a sufficient degree whereby the edge 21 will minimise side loading on the lever 11 due to wave movement. The plunger is reciprocated by the float due to wave movement or boat movement.

A flexible pump suction pipe 22, preferably formed from a plastic material such as polythene, is connected at one end to the inlet 3 and has its other end located in a bilge of the boat.

I claim:

1. A wave-actuated boat pump comprising, a barrel having a closed bottom and an open top, said open top forming an outlet in said barrel, means for removably attaching said barrel to the outside of a boat, an inlet to said barrel adjacent said bottom for receiving a flexible inlet pipe, a foot valve in said barrel above said inlet, a plunger in said barrel above said foot valve and having a head valve therein, a rod carried by said plunger and projecting from said open top of said barrel, a float adapted to ride on the surface of the water, movable means connecting said float to said rod, whereby relative motion between the surface of the water and the boat causes vertical movement of said float to actuate said plunger.
2. Wave-actuated boat pump according to claim 1 wherein the pump outlet is located below water level for the purpose of maintaining automatic priming.
3. Wave-actuated boat pump according to claim 1 wherein the float is a saucer-like vessel constructed to be substantially submerged.
4. A wave-actuated boat pump according to claim 3, wherein, said float is provided with a fine peripheral edge adapted to ride upon the surface of the water.
5. A wave-actuated boat pump according to claim 1, wherein, said movable means comprises a lever fulcrummed at one end on said attaching means and having its free end connected to said float.
6. A wave-actuated boat pump according to claim 5, wherein said attaching means includes a bracket having side guides and upper and lower stops to limit the movement of said lever.
